UNITED STATES PATENT OFFICE.

GEORGE HENRY TYLER, OF MANNVILLE, WISCONSIN.

DRILL.

SPECIFICATION forming part of Letters Patent No. 417,610, dated December 17, 1889.

Application filed August 26, 1889. Serial No. 321,989. (No model.)

To all whom it may concern:

Be it known that I, GEORGE HENRY TYLER, a citizen of the United States, residing at Mannville, in the county of Marathon and 5 State of Wisconsin, have invented a new and useful Drill, of which the following is a specification.

My invention relates to improvements in ratchet-drills, and has for its object the 10 provision of a simple and easily-operated metal-working drill especially adapted for use in railroad-shops.

The invention consists in certain novel features hereinafter described and claimed.

15 In the accompanying drawings, Figure 1 is a perspective view of my improved drill. Fig. 2 is a longitudinal section of the same. Figs. 3 and 4 are detail views. Fig. 5 is a view of a modified form of securing base- 20 piece.

Referring to the drawings by letter, A designates the body of my improved drill, to one end of which I swivel the chuck B, in which the drill-blade C is secured. This 25 chuck is provided with a gear-wheel D, which meshes with a gear-wheel E on the driving-shaft F, projecting from one side of the body, and the said driving-shaft is provided at its outer end with the reversely - arranged 30 ratchet-wheels G G, as shown. The operating-lever or crank-handle H is bifurcated at its lower end, and the arms of the bifurcation are mounted on the driving-shaft. Within the body of the operating-lever I provide the 35 reversely - arranged spring-actuated pawls I, which rest on and are adapted to engage the ratchet-wheels. By vibrating the operating-lever the pawls will be made to alternately engage their respective ratchet-wheels 40 and the driving-shaft be thereby rotated.

On the body A of the drill, at a point diametrically opposite the driving-shaft, I provide a stud-shaft, on which I secure a gear-wheel J, across the outer face of which I 45 form a segmental groove K, the walls of which are dovetailed, as clearly shown. Within this groove I fit a block L, having a screw-threaded stem M projecting from its outer side through the groove K. This stem 50 is engaged by a longitudinally-slotted lever N, which is fulcrumed on a post O, projecting from the body above the gear-wheel J,

and has a pawl P mounted on its upper end. A thumb-nut Q is mounted on the stem M of the block L and is adapted to be turned up 55 thereon against the lever N, so as to secure the said lever on the stem and also secure the block firmly at the desired point of the groove. The stroke of this lever can thus be regulated at will by shifting the block to different points of the groove. The post O is provided with a handle R, by means of which the device may be steadied while in operation, and the pawl P is pressed normally downward by a spring S, secured to the pivot of the pawl and bearing on the pawl. An annular flange or shoulder T is provided on a tubular socket R⁴ and has ratchet-teeth U on its upper side, and the said ratchet-teeth are engaged by the pawl P. This socket R⁴ is secured upon a spindle 70 X², which depends from a base-plate X, and is internally threaded. The said spindle is engaged by the externally-threaded rod V, so that when the socket is rotated the threaded connection between the spindle and rod will 75 cause the body to have a longitudinal movement and thereby feed the drill forward, so as to hold it to its work.

It will be seen that the rod V is swiveled in the body, so that when it turns it will not turn 80 the body. The base-piece X is rigidly fixed in place to any suitable support. Under certain circumstances I may employ the form of base-piece shown in Fig. 5, in which double prongs are used in place of the circular bearing-plate. 85

From the foregoing description, taken in connection with the accompanying drawings, it will be seen that I have provided a very compactly arranged drill which will occupy very little room and which can be easily and 90 rapidly operated. The device is placed in position in the usual manner, with the base-piece X resting against the body of the operator or any suitable fixed support, and the drill-blade placed against the rail or object 95 to be bored. The handle R is then grasped, so as to steady the device, and the operating-lever is then vibrated, so as to operate the machine. As the lever is vibrated a rotary motion will be imparted to the driving-shaft 100 and the drill-blade, so that the drill will be made to form the bore, as will be readily understood. The motion of the driving-shaft and the chuck will be communicated directly

to the gear-wheel J, and the lever N will consequently be vibrated, so as to cause the pawl and the ratchet shoulder or flange to feed the body of the drill forward step by step. The 5 drill will thus be fed to the work as the opening is formed therein, and the desired end quickly and easily accomplished.

The ratchet-wheels and the pawl are reversely arranged, so that one of them is engaged on the forward stroke of the lever to rotate the driving-wheel, while the other wheel will be engaged on the reverse stroke of the lever to prevent retrograde movement of the machine. The motion of the driving-wheel 15 is communicated directly to the gear-wheel D, so that the drill will be operated. The wheel J will also be simultaneously rotated and the slide will act as a crank on the lever to vibrate the same, the slot in the lever allowing the post to move freely without binding on the lever.

Having thus described my invention, what I claim, and desire to secure by Letters Patent, is—

1. The combination of the drill-body, the chuck swiveled at one end of the body, the driving-shaft mounted on one side of the body, intermeshing gear-wheels on the chuck and the driving-shaft, the reversely-arranged 25 ratchet-wheels at the outer end of the driving-shaft, the operating-lever having its lower end bifurcated and the arms of the bifurcation mounted on the driving-shaft on opposite sides of the driving-wheels, and the reversely-arranged spring-pawls mounted in the 30 body of the operating-lever and engaging the ratchet-wheels, as set forth.

2. The combination of the socket R⁴, provided with the ratchet-teeth U, the base having the spindle X², the rod V, having a threaded connection with the spindle, the lever fulcrumed on the side of the body, the pawl car-

ried by said lever and engaging the ratchet-teeth U, and the mechanism for vibrating said lever, as set forth. 45

3. The combination of the body, the gear-wheel J, mounted thereon, mechanism for rotating said wheel, the ratchet-teeth U on the socket R⁴, the lever fulcrumed on the body and adjustably connected to the gear-wheel J, 50 and the pawl carried by said lever and engaging the ratchet-teeth U, as set forth.

4. The combination of the wheel J, having a segmental groove, the lever N, provided with a longitudinal slot, the block fitted in the segmental groove and having a stem passing through the slot of the lever, and the thumb-nut mounted on said stem and adapted to be turned up against the lever, as set forth. 55

5. In combination with the body A, carrying the swiveled drill-chuck B, the operating mechanism for working the drill-chuck, the threaded rod V, swiveled in the body, the rigid base-piece X, threaded on the rod V, the socket R⁴, turning on the base-piece, the driving-shaft 60 F, and intermediate pawl-and-ratchet mechanism between the driving-shaft and the socket R⁴, for the purpose set forth. 65

6. In combination with the body A, the swiveled drill-chuck, the driving-shaft F, the gearing on the same to drive the drill-chuck, the gear-wheel J on the driving-shaft, having the groove K, the lever fulcrumed to the body and adjustably secured in the groove, the pawl carried by the lever, the socket R, provided with ratchet U, and the base-piece provided with the spindle X², as set forth. 70 75

In testimony that I claim the foregoing as my own I have hereto affixed my signature in presence of two witnesses.

GEORGE HENRY TYLER.
